W. C. Smith.

United States Patent Office.

W. C. SMITH, OF WARRENSBURG, MISSOURI.

Letters Patent No. 95,945, dated October 19, 1869.

IMPROVED BED-BOTTOM.

The Schedule referred to in these Letters Patent and making part of the same.

To all whom it may concern:

Be it known that I, W. C. SMITH, of Warrensburg, in the county of Johnson, and the State of Missouri, have invented a new and improved Bed-Bottom; and that the following description, taken in connection with the accompanying drawings, hereinafter referred to, forms a full and exact specification of the same, wherein I have set forth the nature and principles of my said invention, by which it may be distinguished from all others of a similar class, together with such parts as I claim, and desire to have secured to me by Letters Patent.

In the drawings—

Figure 1 is a perspective view of my invention. *b b* are intended to represent the end rails of a bedstead.

h is one of the side rails, the front rail removed, to show other parts more perfectly.

g g are strips of wood, two inches wide on their horizontal surfaces, and firmly attached to the inner and lower margin of the side rails *h*.

c c c, &c., are transverse slats.

d d d are two pieces of strong web-girthing, or other suitable material, attached to the end rails by

means of the hook and eye, or staple, shown in fig. 2, the hook designated by the letter *n*, and the eye by the letter *m*.

The slats *c*, &c., are securely attached to the girthings at their ends, at regular distances from each other.

a a a, &c., are rollers of wood, about three inches in diameter, and of proportional width, placed midway between the slats, beneath the girth, and attached to it by nails, or otherwise secured, so as to turn when one or more of the slats are depressed, causing the others to rise, thus fitting to the undulations of the body, pressing equally all the parts in contact.

The strips *g g* support the rollers.

I claim, in combination with a bed-bottom, the rollers or pulleys *a*, resting upon the strips *g*; the girths *d* and the slats *c*, rounded on the under side, all constructed as described, and for the purposes set forth.

W. C. SMITH.
